UNITED STATES PATENT OFFICE.

CHESTER MCNEIL, OF CHICAGO, ILLINOIS, ASSIGNOR TO THE UNION SPECIAL SEWING MACHINE COMPANY, OF ILLINOIS.

MACHINE FOR SEWING FABRICS.

SPECIFICATION forming part of Letters Patent No. 531,741, dated January 1, 1895.

Application filed August 10, 1893. Serial No. 482,811. (No model.)

To all whom it may concern:

Be it known that I, CHESTER MCNEIL, of Chicago, county of Cook, State of Illinois, have invented an Improvement in Machines for 5 Sewing Fabrics, of which the following is a specification.

My invention has reference to machines for sewing fabrics and consists of certain improvements which are fully set forth in the following specification and shown in the accompanying drawings, which form a part thereof.

My invention comprehends certain improvements in machines designed to sew long lengths of carpets or other fabrics, and in carrying out my invention I employ a long table or support for the fabric, combined with a railway arranged parallel to the support and upon which a carriage travels, a sewing machine carried upon the carriage and adapted to sew the fabric supported upon the table or support, a traveling rope or power conveyer, a gripping device upon the carriage for connecting or disconnecting it with the traveling rope or power conveyer whereby the said carriage and sewing machine may be caused to travel parallel to the table, and power transmitting devices between the sewing machine and the table or other fixed support whereby when the carriage is moved relatively to the table or support the sewing machine is operated. These various devices may be modified or varied in a variety of ways while still involving the same general features. The support for the fabric, while 35 preferably in the form of a table, may be any means which will hold the fabric in a relative position to the railway so that the sewing machine may properly act upon the edges for the purpose of uniting them.

In the drawings: Figure 1 is a front elevation of a machine for sewing fabrics embodying my invention. Fig. 2 is a cross sectional elevation of same on line $x-x$. Fig. 3 is an enlarged front elevation of the gripping device. Fig. 4 is a front elevation of a modification of my invention. Fig. 5 is a cross sectional elevation of same on line $y-y$ of Fig. 4; and Fig. 6 is an enlarged front elevation of one form of gripping device.

A is the table or support, and as stated

before may be constructed in any suitable manner.

B is the railway arranged along the floor or in any manner so long as it is parallel to the support for the fabric.

C is a carriage of any suitable construction traveling upon the railway B and carrying the sewing machine D which may be of any construction, though preferably of the type known as the "Union Special" sewing ma- 60 chine.

G is a rack arranged along the table or held in any suitable manner parallel to the railway track.

E is a band wheel carried upon the carriage 65 C and connected by a band e with the sewing machine D. The band wheel E is arranged to be driven at a high speed by means of suitable gearing F meshing with the rack G. It will be observed that as the carriage C trav- 70 els upon the railway, the said motion imparts a rotation to the shaft of the sewing machine causing it to perform the function of sewing, and the speed of the sewing it will be seen is dependent upon and commensurate with the 75 speed of travel of the carriage as it should be.

H is an endless band guided about guide pulleys at each end of the table or support and is caused to constantly travel about the said guide pulleys by means of an electric or 80 other motor I.

J is a suitable gripping device carried by the carriage and adapted to grasp the endless cable H and thereby propel the carriage. When the handle K of the gripping device is 85 turned to the right or left it operates an eccentric l thereby causing the jaws of the grip to tighten upon the traveling cable H imparting motion to the carriage C.

It will be evident that if the cable H were 90 made to directly operate the sewing machine, difficulties would arise from the fact that the sewing machine would be operating at a constant speed irrespective of the travel of the carriage relatively to the fabric, which would 95 be undesirable. By my improvement, however, the operation of the sewing machine is commensurate with the travel of the carriage C so that every stitch is of the same length whether the carriage is moving fast or slow. 100

It will be understood that I do not confine myself to any particular construction of power device between the stationary rack G and the sewing machine D as a large variety of ways may be employed for imparting motive power to the sewing machine, though that shown is excellently adapted to the purpose. A clutch f may be employed to disconnect the band wheel E from the gearing F to be used when the machine is to be run backward, but it is also clear that various methods may be employed to throw off the operation of the sewing machine during the return of the carriage. In some types of sewing machines there is a clutch upon the band wheel, and this might be connected or disconnected as required.

In the construction shown on sheet 2 I have the endless cable H, and in place of the rigid grip J, I provide a clutch shown in Fig. 6 consisting of four pulleys M arranged in pairs, two of which are carried upon spring bearings N. A frame n acts upon the outer ends of the spring bearings to depress them until the cable H is grasped under the action of an eccentric k moved by a lever K. When the spring bearings are depressed the pulleys M carried by said spring bearings are forced toward the pulleys M carried upon the stationary part of the grip, and this gradually grips the cable H with an elastic pressure, overcoming the danger to the apparatus which would result from suddenly gripping the cable. This device constitutes an elastic gripping device and is the preferable form. The table or support and carriage, sewing machine, pulleys E, band e, and gear F are substantially the same in the construction shown in Figs. 4 and 5 as in the case of Figs. 1 and 2. In place of the rack G, a stationary cable G' is employed in the modification, the said cable being passed about a pulley L adapted to drive a gearing F for operating the sewing machine. The movement of the carriage C causes the pulley L to travel on the stationary cable G' and thereby cause it to rotate with the speed commensurate to that of the travel of the carriage, thus causing the sewing machine to operate at the proper speed to insure uniform stitches when uniting the fabric.

I do not confine myself to any special details of construction as they may be modified more or less without departing from the principles of the invention.

What I claim as new, and desire to secure by Letters Patent, is—

1. In a machine for sewing fabrics, the combination of a support for the fabric, a railway parallel to the support, a carriage adapted to travel upon the railway, a sewing machine secured to the carriage, the traveling cable, the grip secured to the carriage adapted to

grasp the cable, and power devices for operating the sewing machine substantially as set out.

2. In a machine for sewing fabrics, the combination of a support for the fabric, a railway parallel to the support, a carriage adapted to travel upon the railway, a sewing machine secured to the carriage, the traveling cable, the grip secured to the carriage adapted to grasp the cable, and power devices for operating the sewing machine consisting of a stationary part arranged parallel to the railway, a rotary part journaled upon the carriage and adapted to be rotated by the stationary part through frictional contact, and power transmitting devices between the rotary part and sewing machine substantially as set out.

3. In a machine for sewing fabrics, the combination of a support for the fabric, a railway parallel to the support, a carriage adapted to travel upon the railway, a sewing machine secured to the carriage, the traveling cable, the grip secured to the carriage adapted to grasp the cable, power devices for operating the sewing machine consisting of a stationary rack arranged parallel to the railway, gearing journaled upon the carriage and meshing with the said rack, and power transmitting connections between the gearing and the sewing machine substantially as set out.

4. In a machine for sewing fabrics, the combination of a support for the fabric, a railway parallel to the support, a carriage adapted to travel upon the railway, a sewing machine secured to the carriage, the traveling cable, the grip secured to the carriage adapted to grasp the cable, and power devices for operating the sewing machine consisting of a stationary rack arranged parallel to the railway, gearing journaled upon the carriage and meshing with the said rack, and power transmitting connections between the gearing and the sewing machine, and means for throwing the sewing machine into or out of action substantially as set out.

5. In a machine for sewing fabrics, the combination of a support for the fabric, a railway parallel to the support, a carriage adapted to travel upon the railway, a sewing machine secured to the carriage, a traveling cable, power devices for operating the sewing machine, and a grip carried with the carriage and having flexible or elastic gripping devices for gradually gripping the traveling cable to start the sewing machine gradually from a state of rest.

In testimony of which invention I have hereunto set my hand.

CHESTER MCNEIL.
